UNITED STATES PATENT OFFICE.

CHARLES WAINWRIGHT, OF ERIE, PENNSYLVANIA.

PLATE-VALVE.

1,214,336.

Specification of Letters Patent. Patented Jan. 30, 1917.

Application filed July 30, 1915. Serial No. 42,851.

To all whom it may concern:

Be it known that I, CHARLES WAINWRIGHT, a citizen of the United States, residing at Erie, in the county of Erie and State of Pennsylvania, have invented new and useful Improvements in Plate-Valves, of which the following is a specification.

This invention relates to plate valves for compressor service and it consists in the novel features hereinafter described and claimed.

An object of the invention is to provide a valve of the character indicated having maximum discharge port way or area for a given size valve, or, in other words, whose area through the valve lift is equal to or greater than the area through the seat.

Another object of the invention is to provide a valve structure of durable and light nature and one through which the resistance to the flow of air or gas is reduced to a minimum. At the same time a flexible, simple and tight valve is provided.

With the above objects in view the valve includes a seat body having a single inlet port and a plurality of outlet ports. Flexible valve tongues are arranged above the body and are adapted to close the spaces between the seat bars thereof. A frame is positioned upon the body and serves as means for limiting the movement of the tongues away from the valve seat as the air or gas is forced through the spaces between the seat bars.

Among the characteristics of the valve the following are noted: In operation the valve tongues bend away from the seat to permit the passage of air or gas through the spaces between the seat. The valve tongues are light and flexible, offering a minimum resistance of both inertia and friction to the passage of air or gas, a minimum destructive action in closing and tightness after closing, due to the intimate contact with the seat permitted by the flexible character of the valve tongues.

In the accompanying drawing:—Figure 1 is a top plan view of the valve with parts broken away. Fig. 2 is a transverse sectional view of the same cut on the line 2—2 of Fig. 1. Fig. 3 is an under plan view of the valve. Fig. 4 is a transverse sectional view of the valve cut on the line 4—4 of Fig. 1. Fig. 5 is a plan view of the tongues used upon the valve.

The valve includes a seat body 1 having a

single admission port 2 and a plurality of exit ports 3. The body 1 is further provided with seat bars 4 which are spaced from each other and which separate the exit ports 3 one from the other. A tongue member 5 of thin pliable metal is provided and the said tongue member is secured to the body member 1 at the top side thereof and along one edge thereof as best indicated in Figs. 1 and 4 of the drawing. The tongue member 5 is divided into a plurality of tongues 6 which correspond in number with the exit ports 3. The tongue members 6 normally lie above the ports 3 and they may close against the seat bars 4 along the exit ports 3 in a manner as best indicated in Fig. 2 of the drawing. A frame member 7 is secured above the tongue member 5 and is connected with the body member 1 by means of screws 8 or other suitable securing devices. The said screws 8 also pass through the edge portion of the tongue member 5. The frame member 7 is provided with a number of spaced parallel bars 9 which are located directly above the tongues 6 of the tongue member 5. In this form of the invention it is apparent that when air or gas is forced through the valve structure and enters the body 1 through the admission port 2 the pressure of the air or gas against the under sides of the tongues 6 moves the said tongues away from the seat bars 4 consequently the air or gas may pass through the exit ports 3 and but slight resistance is presented on the part of the tongues 6. Therefore the valve possesses maximum discharge port area for a given size of valve and this area through the valve lift or tongue lift is equal to or greater than the area through the seat, therefore, the tongues do not offer material resistance to the free passage of the air or gas through the valve structure.

As indicated in Fig. 4 of the drawing the tongues 6 may be independent of each other and each of the said tongues is provided in the vicinity of that end where it is secured to the body 1 with a kink 11 which materially adds to the flexibility of the tongue and also increases its scope of swinging movement with relation to the seat bars 4 when the tongue is forced away from the said bars by the passage of air or gas through the valve structure.

From the above description taken in conjunction with the accompanying drawing it will be seen that a valve structure of simple

and durable arrangement is provided and that the valve may operate in the absence of noise, undue friction and not present resistance to the free passage of the air or gas. Having described the invention what is claimed is:—

A valve comprising a body having an admission port and a plurality of exhaust ports, tongues mounted upon the body and adapted to close over the exhaust ports, said

tongues being provided in the vicinity of their points of attachment with the body with laterally disposed kinks.

In testimony whereof I affix my signature in presence of two witnesses.

CHARLES WAINWRIGHT.
